ERNST KOERTING, OF PEGLI, NEAR GENOA, ITALY, ASSIGNOR TO SCHUTTE & KOERTING COMPANY, OF PHILADELPHIA, PENNSYLVANIA, A CORPORATION OF PENNSYLVANIA.

JET APPARATUS.

1,158,239.

Specification of Letters Patent. Patented Oct. 26, 1915.

Application filed March 15, 1912. Serial No. 683,949.

To all whom it may concern:

Be it known that I, ERNST KOERTING, a subject of the German Emperor, residing at Pegli, near Genoa, Italy, have invented certain new and useful Improvements in Jet Apparatus, fully described and represented in the following specification and the accompanying drawings, forming a part of the same.

10 This invention relates to a jet apparatus in which a forcing jet of water or other liquid serves as the forcing or actuating means for the transportation or movement of air or other gases.

15 The object of the invention is to increase the efficiency, and more especially the capacity, of a high pressure jet apparatus, that is, one in which the momentum of the jet is sufficient to force the gas against a considerable difference in pressure between the suction side and the discharge side of the apparatus, whether used as a suction or a forcing or compressing pump, or as a condenser. To this end I provide the apparatus with means to produce fissures in the jet into which the gas may enter to get to the core of the jet, means being preferably provided also for facilitating the entrance of the gas into such fissures. By 20 producing such gas-receiving fissures in the actuating jet, the surface area of the liquid with which the gas comes into contact is greatly increased, while the direction of flow of the jet is not affected and the energy 25 of the jet is not substantially diminished.

30 A full understanding of the invention can best be given by a detailed description of an apparatus embodying the various features of the invention in an approved form, and such a description will now be given in connection with the accompanying drawings, in which,

35 Figure 1 is a central sectional view of a simple form of apparatus made in accordance with the invention. Fig. 2 is a section of the water jet nozzle taken on line 2 of Fig. 1. Fig. 3 is a similar view of a further modification. Fig. 4 is a section taken on line 4 of Fig. 3.

40 Referring to the drawings, and first to Figs. 1 and 2, the water jet nozzle 10 extends into a supply chamber 11 in position to discharge water received from the water supply pipe 12 in the form of a jet into the 45 end of a combining tube 13 which extends some distance into the supply chamber 11.

The combining tube discharges through a diverging discharge tube or pressure cone 14. The air, steam or other gas enters the supply chamber 11 through an inlet 15. In order to form the gas-receiving fissures in the solid jet the nozzle 10 is provided at its discharge end or mouth with one or more jet openers 20 extending inward from the nozzle wall, there being preferably a plurality of such openers arranged radially as shown in Figs. 2 and 3. These openers may extend clear in to the axial line of the nozzle as shown in Figs. 1 and 2 or the openers may end short of the axial line as shown in Figs. 70 3 and 4. The openers are best made of inwardly tapering form as shown so that the fissures in the jet will be of inwardly tapering or wedge shape, and the openers are best made of a depth or length in the direction of the movement of the jet considerably greater than their thickness and with their upper or outer portions tapered off to provide sharp edges, thus insuring a straight flow without oscillation. As the opened jet 80 issues from the nozzle and enters the combining tube, the gas from the chamber 11 will not only come in contact with the outer surface of the jet and be drawn into the combining tube through such contact, but 85 will also enter the fissures in the jet, and the extent of surface of the jet with which the gas comes in contact and, consequently, the volume of gas carried through the combining tube will thus be greatly increased; 90 and this result is secured without substantially interfering with the flow of the jet or affecting its velocity, so that the jet retains substantially the momentum and propelling energy of a solid jet. To secure the 95 greatest benefit from the increased area of contact between the liquid and the gas due to the fissures in the jet the combining tube is formed with openings in its upper portion in line with the openers 20 through 100 which gas from the chamber 11 may pass to enter the fissures in the jet after the jet has entered the mouth of the combining tube. These openings are shown as formed by longitudinal slits 21 extending from the upper end of the combining tube in alinement with the dividers 20.

105 The nozzle should be set close to the mouth of the combining tube as shown so that the split or fissured jet will come into action in the combining tube so far as possible without loss of the form in which it issues 110

from the nozzle. The shape of the mixing chamber or combining tube and its cross sectional area at its narrowest point will vary according to the character of the gas to be moved. If the gas is such that condensation or absorption by the liquid takes place, the combining tube will be reduced as indicated by dotted lines in Fig. 1 more or less according as the condensation or absorption is perfect or only partial. The length of the combining tube, also, in such case will depend on the rapidity of absorption or condensation and also on the size and number of the fissures formed in the jet.

15 The openers 20 may be formed separately from the nozzle and set removably or permanently in position in the mouth of the nozzle. When the openers end short of the axial line of the nozzle and are not joined together centrally they may be carried by a ring 22 as shown in Figs. 3 and 4. Other arrangements of the openers for producing a fissured jet with comparatively deep and more or less narrow fissures therein may be employed.

20 It will be seen that the apparatus of the invention is a high pressure apparatus, that is, an apparatus in which the actuating jet has such volume and velocity that its momentum or propelling energy is sufficient to force the gas against a considerable difference in pressure between the suction side and the discharge side of the apparatus.

25 What is claimed is:

30 1. A high pressure liquid-jet apparatus, comprising in combination a combining tube, and a pressure cone leading therefrom, and a nozzle formed to discharge a high-velocity impelling jet of liquid into the combining tube, said nozzle having jet openers to form gas-receiving fissures in the jet opening inward from the outer surface of the jet and being a sufficient distance apart to avoid destroying the solidity of the intervening 35 portions of the jet, and the combining tube and pressure cone being formed to permit unimpeded passage of the fissured jet.

40 2. A high pressure liquid-jet apparatus, comprising in combination a combining tube and a pressure cone leading therefrom, and a nozzle formed to discharge a high-velocity impelling jet of liquid into the combining tube, said nozzle having jet openers to form gas-receiving fissures in the jet opening inward from the outer surface of the jet and being a sufficient distance apart to avoid 45 destroying the solidity of the intervening portions of the jet, and means for directing the gas into such fissures, the combining tube and pressure cone being formed to permit unimpeded passage of the fissured jet.

50 3. A high pressure liquid-jet apparatus, comprising in combination a combining tube

and a pressure cone leading therefrom, and a nozzle formed to discharge a high-velocity 55 impelling jet of liquid into the combining tube, said nozzle having jet openers to form gas-receiving fissures in the jet opening inward from the outer surface of the jet and being a sufficient distance apart to avoid destroying the solidity of the intervening 60 portions of the jet, and means for admitting the gas to said fissures beyond the entrance end of the combining tube, the combining tube and pressure cone being formed to permit 65 unimpeded passage of the fissured jet.

4. A high pressure liquid-jet apparatus comprising in combination a jet nozzle, a combining tube, a pressure cone, and means for opening the jet to form gas-receiving 80 fissures therein opening inward from the outer surface of the jet, said parts being formed and arranged to cause the fissured jet to flow through the combining tube without substantial loss of forward velocity and 85 propelling energy, and the combining tube being formed with openings for admitting the gas to the fissures in the jet.

5. A high pressure liquid-jet apparatus comprising in combination a combining 90 tube, a pressure cone, and a jet nozzle provided with jet openers of inwardly tapering form and ending short of the axial line of the nozzle for forming gas-receiving fissures 95 in the jet, said parts being formed and arranged to cause the fissured jet to flow through the combining tube without substantial loss of forward velocity and propelling energy.

6. A high pressure liquid-jet apparatus 100 comprising in combination a combining tube, a pressure cone, and a jet nozzle provided with a removable ring set into the mouth of the nozzle and carrying a plurality of inwardly extending jet openers ending 105 short of the axial line of the nozzle for forming gas-receiving fissures in the jet, said parts being formed and arranged to cause the fissured jet to flow through the combining tube without substantial loss of 110 forward velocity and propelling energy.

7. In a liquid jet apparatus, the combination of a jet nozzle provided with radial jet openers set in the mouth of the nozzle to form radial fissures in the jet, and a combining tube formed with longitudinal slits 115 through the sides of the tube in alignment with the openers for admitting the gas to the fissures in the jet.

In testimony whereof, I have hereunto 120 set my hand, in the presence of two subscribing witnesses.

ERNST KOERTING.
